Primary Examiner — Wan Laymon(74) *Attorney, Agent, or Firm* — Morgan, Lewis & Bockius LLP**CLAIM**

The ornamental design for a fluid transfer device, as shown and described.

DESCRIPTION

FIG. 1 is a front perspective view of a fluid transfer device in accordance with our new design;

FIG. 2 is a front plan view of the fluid transfer device shown in FIG. 1;

FIG. 3 is a rear plan view of the fluid transfer device shown in FIG. 1;

FIG. 4 is a right-side elevational view of the fluid transfer device shown in FIG. 1;

FIG. 5 is a left-side elevational view of the fluid transfer device shown in FIG. 1;

FIG. 6 is a top elevational view of the fluid transfer device shown in FIG. 1; and,

FIG. 7 is a bottom elevational view of the fluid transfer device shown in FIG. 1.

The broken lines in the figures are for illustrative purposes only and form no part of the claimed design.
